(57) **CLAIM**

The ornamental design for a vapor tube, as shown and described.

DESCRIPTION

FIG. 1 is a top perspective view of a vapor tube showing my new design;

FIG. 2 is a front elevational view thereof, the opposite side not shown is a mirror image thereof;

FIG. 3 is a left side elevational view thereof, the opposite side not shown is a mirror image thereof;

FIG. 4 is a top plan view thereof;

FIG. 5 is a bottom plan view thereof;

FIG. 6 is an exploded bottom perspective view thereof;

FIG. 7 is a top perspective view thereof;

FIG. 8 is a top perspective view of a second embodiment showing my new design;

FIG. 10 is a front elevational view thereof, it being understood that the opposite side not shown is a substantial mirror image thereof;

FIG. 11 is left side elevational view thereof, it being understood that the opposite side not shown is a substantial mirror image thereof;

FIG. 12 is a top plan view thereof;

FIG. 13 is a bottom plan view thereof;

FIG. 14 is an exploded bottom perspective view thereof;

FIG. 15 is a top perspective view of a third embodiment showing my new design;

FIG. 16 is a front elevational view thereof, it being understood that the opposite side not shown is a substantial mirror image thereof;

FIG. 17 is a left side elevational view thereof, it being understood that the opposite side not shown is a substantial mirror image thereof;

FIG. 18 is a top plan view thereof;

FIG. 19 is a bottom plan view thereof;

FIG. 20 is an exploded bottom perspective view thereof;

FIG. 21 is a top elevational view thereof; and,

FIG. 22 is a top elevational view thereof.

In the drawings, the broken lines depict environmental subject matter only and form no part of the claimed design.

Law(57) **CLAIM**

The ornamental design for a vapor tube, as shown and described.

DESCRIPTION

FIG. 1 is a top perspective view of a vapor tube showing my new design;

FIG. 2 is a front elevational view thereof, the opposite side not shown is a mirror image thereof;

FIG. 3 is a left side elevational view thereof, the opposite side not shown is a mirror image thereof;

FIG. 4 is a top plan view thereof;

FIG. 5 is a bottom plan view thereof;

FIG. 6 is an exploded bottom perspective view thereof;

FIG. 7 is a top perspective view thereof; and,

FIG. 8 is a top perspective view thereof.

In the drawings, the broken lines depict environmental subject matter only and form no part of the claimed design.
